UNITED STATES PATENT OFFICE.

ABRAHAM S. MEADOFF, OF NEW YORK, N. Y., ASSIGNOR TO SUSPENSION BED SPRING MANUFACTURING COMPANY, OF NEW YORK, N. Y., A CORPORATION OF NEW YORK.

FOLDING COT-BED.

1,110,812.

Specification of Letters Patent. Patented Sept. 15, 1914.

Application filed August 13, 1913. Serial No. 784,474.

To all whom it may concern:

Be it known that I, ABRAHAM S. MEADOFF, a citizen of the United States of America, and a resident of New York, in the county 5 and State of New York, have invented certain new and useful Improvements in Folding Cot-Beds, of which the following is a specification.

This invention has reference to improvements in folding cot beds.

It pertains particularly to a portable bed which is provided with a light frame folded upon central supports of relatively great strength which supports form the principal 15 legs of the bed both when in use and when stored away. These supports, being practically in the center of the bed where the strain is greatest, increase its durability. The central supports are further provided 20 with narrow cross braces whereby additional strength is added to the structure. The braces are narrow because the supports are very narrow, the folded bed occupying only a few inches in length while the width 25 of the bed remains normal.

There are means in connection with the bed frame parts for forming outside legs and means for imparting elasticity to the 30 canvas or woven wire spring. When folded the portable bed need not be leaned against a wall because it rests on the four legs of the two supports. Between the frame parts bedding, pillows and the like may be stored during day time. In addition to these main 35 objects care has been taken to produce a neat and desirable but durable article of relatively little cost, all as will be fully described hereinafter with reference to the accompanying drawing in which:

40 Figure 1 represents the portable folding cot bed in side elevation unfolded and in dotted lines in the folded condition. Fig. 2 illustrates the central and head part of the folding bed in top plan view, on an enlarged 45 scale. Fig. 3 is a cross section on line 3—3 of Fig. 2.

Similar characters of reference denote like parts in all the figures.

On the drawing a , a^1 represent the two 50 central supports. Each support forms two downward legs b , b^1 provided at the bottom with rollers c , c^1 . The top portion of each support has screwed thereto a rectangular side brace d . Cross braces e , e^1 connect the 55 two supports as shown in Fig. 2. To the

rectangular braces d the frame is pivotally secured. This frame consists of two parts f , g . The frame part f is secured to the adjoining side end of the brace d by means of pivots h and the frame part g to the opposite end of said brace by means of pivots i . From each front end portion of the frame part f a leg k extends downwardly in a somewhat slanting direction. The leg k is movably secured to the frame part f by means of a 60 pivot l . A brace m is pivotally secured with one end to the leg k and with its other end to the leg b of the central support. Each rear end portion of the frame g is likewise provided with a movable leg n and a movable brace o . The braces o of course are connected each with the inner end to a leg b^1 of the central support. The lower portions 65 of the legs k are connected by a rod p and the lower portions of the legs n are connected by a similar rod p^1 . These rods lodge in the incisions p^2 , p^3 of the braces m , o when the frame is folded. This insures a hold of one folded frame in position when the other is folded. A top brace q further 70 tends to hold the folded frames securely. A rod in an incision likewise holds one frame part in position when the other is pressed down during the opening of the bed. When folding the bed the legs k , n and the 75 braces m , o are close to the frame as shown in Fig. 1. To strengthen the central support especially in the closed position, two rods r , s pass through the lower portions of the legs b , b^1 .

Underneath the rectangular cross brace d devices are provided to impart spring action or a cushion effect to the canvas or woven wire spring z . Such device is shown in Fig. 3 and comprises a hollow bottom part t 95 secured to the brace d by a rivet u and a bolt v which passes through the top of the angular brace d and through the cross brace e in a downward direction into the hollow part t . A helical spring w is provided on said bolt resting with its bottom end on the hollow part t while its top end bears against the cross brace e . When someone lies down the springs w are depressed, and when arising the springs expand.

The rear frame part g has in each long side an incision x^1 . A pillow frame y is pivotally secured to the frame part g and rests on a slantingly cut portion of said part g at either side as shown at y^1 . The pillow 110

frame y extends beyond the frame part g at a desirable distance as shown in Fig. 2, so that this convenience for resting the head a little higher in fact tends to shorten the whole device when in the folded condition. As shown on the drawing the pillow frame y is turned over to rest on the inner side of the frame part g and thus is entirely out of the way when the bed has been folded.

10 The canvas or wire spring z is best mounted on a light separate frame and may be provided with springs z^1 at its sides as shown in Fig. 2. The canvas frame may be foldable and in case a wire spring is used 15 the same may be rolled. The springs z^1 may be provided with downward hooks at their outer ends so as to secure either a canvas or a wire spring in the top portions of the frame parts f , g . If the canvas is solely 20 provided with the springs it may be easily folded. The hooks of the springs z^1 permit of an easy insertion and removal of the canvas or wire spring. As shown in Fig. 1, 25 bedding pillows and the canvas may be stored between the closed frame parts f , g when the bed is folded.

I claim as my invention:

1. A portable cot bed adapted to be folded into a very narrow space comprising two 30 narrow central side supports forming each two rigid legs, a rectangular brace secured to the top portion of each support, a pair of cross braces underneath the rectangular braces, means in connection with the rectangular braces and cross braces to impart 35

a cushion effect, and folding bed frames connected at each side of the rectangular braces.

2. A portable cot bed adapted to be folded into a very narrow space comprising two 40 narrow central side supports forming each two rigid legs, a rectangular brace secured to the top portion of each support, a pair of cross braces underneath the rectangular braces, bolts passing through the rectangular braces and cross braces, stationary supports below for said bolts, and springs on said bolts bearing against the cross braces, and folding bed frames connected at each 45 side of the rectangular braces. 50

3. A portable cot bed adapted to be folded into a very narrow space comprising two narrow central side supports forming each two rigid legs, a rectangular brace secured to the top portion of each support, a pair 55 of cross braces underneath the rectangular braces, bolts passing through the rectangular braces and cross braces, stationary supports below for said bolts, and springs on said bolts bearing against the cross braces, 60 folding bed frames connected at each side of the rectangular braces, and means for supporting the bed frames when open and locking them when folded.

Signed at New York, N. Y., this 9th day 65 of August, 1913.

ABRAHAM S. MEADOFF.
